QUIET FLOW RETARDING DEVICE

Walker F. Peterson and Albert U. Walter, Baltimore, Md., assignors, by mesne assignments, to Baltimore Valve Corporation, Baltimore, Md., a corporation of Maryland

Application July 31, 1934, Serial No. 737,842

6 Claims. (Cl. 138—40)

This invention is a new and useful device and operates for throttling or retarding the flow of liquids with a minimum of noise at the device and in the apparatus as a whole.

5 An object of this invention is to provide quiet, simple and inexpensive means for retarding the flow of liquid at some point in the distributing system so as to reduce the velocity of flow in the rest of the system to such an extent that objectionable noise will be reduced or eliminated.

Another object of the invention is to provide simple and inexpensive means for reducing the noise occurring in toilet flushing tanks, both during the full flow for refilling the tank, and 15 during the termination or final shut-off of such flow at the ball cock or float valve thereof.

Further features and objects of the invention will appear in the course of the following specification and claims.

20 Since a toilet flushing tank with its ball cock or float valve provides a common instance of an apparatus in which noise is undesirable, such an apparatus is used illustratively in this description as an example of employment of the 25 retarding device and apparatus of the present invention.

In the accompanying drawing:

Figure 1 is an upright sectional view through a toilet flushing tank having therein a retarding device embodying the present invention;

Figure 2 is an upright sectional view on a larger scale through the float valve structure;

Figure 3 is a side elevation of a quieting discharge device as shown in Figures 1 and 2;

35 Figure 4 is an end view of the same;

Figure 5 is a view corresponding to Figure 1, of a modified form of employment of the invention.

It is known that the flow of a confined liquid 40 such as water, under pressure, in pipes, valves and fittings, causes noise when the velocity of the water exceeds certain limits. Such a limit of velocity, above which noise occurs and herein called the critical velocity, depends upon many 45 conditions. Water at a relatively low velocity will cause noise if there is an abrupt or sudden change in the direction or rate of flow, while water at a much higher velocity will not cause noise if the change in direction or rate of flow is more gradual. Among other factors determining the critical velocity above which noise 50 will occur, and the amount and character of noise which occurs at a given velocity, are the amount of absorbed gases contained in the water, 55 the vapor tension of the water due to its tem-

perature, and the absolute pressure of the water downstreamward, or at the low pressure side, of the restriction, obstruction or void.

The above is more or less generally known in the art and many devices have been proposed 5 and used for retarding the flow below the critical velocity at which noise occurs or in other words to obtain quietness. Some of such devices have been successful in reducing the flow and thereby reducing or eliminating the noise where 10 it previously occurred but they are noisy in themselves and thereby accomplish no net results. Other devices have been successful in quietly retarding the flow and eliminating the noise elsewhere but their rate of flow has been 15 insufficient for practical purposes. Such devices generally comprising long tortuous passageways, are cumbersome, complicated and expensive.

A round discharge tube leading from the body of the float valve into the tank, commonly called 20 the hush tube, of sufficiently small internal diameter to provide the proper amount of retardation for satisfactory quiet performance at the valve proper, operates fairly quietly in itself. However, such a retarding device has so high a 25 discharge velocity and such a small perimeter for its cross-sectional area as to create considerable noise under high pressure at discharge into the tank and to create a violent and undesirable turbulence in the tank itself. 30

Therefore the problem is to obtain a retarding device with sufficient flow for practical purposes, which is quiet in itself, which does not cause objectionable turbulence in the tank and which, at the same time, is compact, simple and 35 inexpensive.

In the employment of such devices where the liquid is to be discharged into an open receptacle, the absolute pressure at discharge is close to atmospheric, and pressure differential effects 40 have demanded consideration in design of quiet retarding devices.

With the illustrated toilet flushing tank as an example, the water comes to rest at atmospheric pressure at or following the refilling period. A 45 certain minimum volume flow per unit of time is demanded in order to obtain satisfactory operating conditions, and hence there is a certain minimum cross-section of flow required under operating pressures. These operating pressures 50 themselves vary from place to place within a given city; and usually vary from hour to hour even at the same outlet, due to varying consumptions in the city; hence, the device for retarding the flow must be operative under consid- 55

erable variations of pressure condition, of temperature, and of absorbed gases.

It has been found that the shape of the cross-section of flow and of discharge has a most important influence upon the amount of noise or upon the critical velocity at which noise occurs; and that the thinner or narrower the cross-section, the quieter the flow, or the higher the critical velocity above which noise occurs. In particular, a desirable cross-section of flow can be obtained in a very simple, cheap and effective manner by simply flattening a section of a tube.

An essential point of the invention, therefore, is to provide a passage for the liquid of such cross-section that a thin sheet of liquid is maintained between opposite walls, so that each filament in the flowing stream is closely adjacent to a wall which produces a retarding effect directly or indirectly thereon. Further, in the illustrated forms, such a cross-section of flow continues beyond the point of discharge so that a thin, wide sheet of liquid is discharged into a general body of liquid, the discharge orifice being spaced from all walls of the chamber containing this free body of liquid, so that the liquid in the free body may be carried along with the newly issuing liquid and thus effect a marked, yet constant, retarding influence thereupon.

With such a cross-section of flow within the tube and discharge, a maximum perimeter for a given cross-sectional area of flow is obtained. This gives a maximum retarding effect by the walls of the tube and by the general body of free liquid in the tank. Such a cross-section of flow presents the greatest contact surface per unit of volume of flow, and hence gives the most effective deceleration of the entering liquid. Thus a minimum of turbulence is set up. It has been found that this is one of the more important considerations in obtaining quiet retardation of flow.

In the drawing, the flush tank or receptacle 10 is conventionally illustrated as having a discharge 11 controlled by a valve 11a and a water supply pipe 12. These pipes pass through the bottom of the tank and are sealed in the usual manner. Inside of the tank the riser supply connection 13 leads to the float valve head 14 which has the usual valve closure 15 movable therein to shut off the flow of water. This closure member is controlled by the usual valve float 15a. The inner chamber of the head 14, downstreamward of the valve seat, is in free communication with a drop conduit 16 which here operates as a back-pressure producing and silent discharge device.

This device is illustrated in a simple form which can be produced by threading one end 16a of a tube so that the device is supported in the head 14. This is the inlet end of the tube. The tube is flattened from its other or outlet end for a distance of say three or more inches. This is permitted by the normal size and shape of those parts which are substantially standardized at the present time. This flattening is so effected in the illustrated form that plane parallel opposed walls are provided. Said walls are closely spaced and joined by simple arches at their ends. Such a device for the standard ball cock may be formed of standard tubing of one-half inch outside diameter and of the desired length, this tubing being threaded and flattened as stated above. The perimeter of the tubing remains substantially unchanged, but a gradual transi-

tion or change of shape is provided from the cylindrical threaded portion to the flat restricted passageway portion. In other words, the tube from end to end has its cross-sections of substantially equal perimeter. The distance between the equidistant walls is preferably between .030 and .060 inch. While this distance may be selected according to the pressure differential when the liquid pressure is uniform, it has been found advantageous to prepare standard devices as shown in Figures 3 and 4 for water closet flush tanks using tubing with one-half inch outside diameter and one-thirty-second inch walls with this distance of separation about .030 inch so that the device is effective for quietly retarding flows where the pressure differential when the valve is in operation varies from twenty-five to one hundred pounds per square inch. The refilling time when used with the standard flush tank varies from about seventy-five to around thirty seconds. This device, therefore, permits a quiet refilling within the satisfactory time period under all normal conditions of service.

In practical tests with such devices, however, it is found that the preferred length of three inches or more for the flat portion of the tube 16 is not compulsory. The coefficient of discharge at eighty-five pounds drop in pressure from such a device having its walls spaced .030 for a distance of one-quarter of an inch is over 90 percent; with a similar device having the passage one inch long, under like conditions, the coefficient of flow is less than 80 percent.

It will be noted that the device extends into the tank or receptacle and into the water which collects in the tank during the refilling period, and that the lower end or orifice is spaced from the walls of the tank so that the water already present can flow downwardly outside of the tube 40 toward the orifice. The orifice is thus provided by the thin walls of the tube itself at a point where the water already in the tank may meet the water newly issuing through the orifice in a direction substantially parallel to that of the movement of the entering water. This arrangement has been found of great advantage, especially at high pressure differentials, in reducing noise.

In practice, it is found that such an apparatus operates both during the full flow of refilling and during the shut-off period with such freedom from noise under the various pressure conditions, that the operation is practically inaudible at a distance of a few feet.

While the form shown in Figures 1 and 2 concerns the discharge into a tank at atmospheric pressure, it is also possible to employ a device under conditions where the discharge pressure is considerably above atmospheric. An arrangement capable of operation between the point of supply and a control valve is shown in Figure 5, where the supply pipe 12a communicates through the cap 20 with the interior of a conduit 21 of larger section for providing a chamber or receptacle for a body of free water. The upper closing cap 22 connects with the discharge pipe 23. A retarding device 16 of the type shown in Figures 3 and 4 is threaded into the lower cap 20, so that the water flowing from supply pipe 12a must pass therethrough. The upper end or orifice of the device 16 is spaced from all walls of the chamber 21. Here again, the restriction in the device and the discharge of the thin wide sheet of water therefrom causes a retardation 75

in the device and in the free body of water which creates the necessary pressure to limit the volume of flow through the pipe 23 with the production of a minimum of noise in the device itself 5 or in the system as a whole.

In its preferred form, therefore, the invention comprises an apparatus for supplying a liquid under pressure, a retarding device having at the inlet end a large cross-section, and a gradual 10 transition portion (to avoid vena contracta effects), and a retarding portion having opposite walls providing a flow passage and space between 0.010 and 0.125 of an inch. These walls are preferably parallel and the device is of substantially 15 the same shape and size for a distance of one-quarter of an inch or more from the delivery end. Appreciable divergence in the direction of flow tends to cause noise whereas convergence reduces the retarding effect. Preferably, the 20 parallel walls terminate at the orifice which is spaced from the walls of the chamber into which the flow is directed. This shaping of the outlet end portion delivers the liquid in a sheet-like form and retards the flow of liquid into the receptacle with consequent substantial elimination 25 of the noise at the device and in the apparatus as a whole as has been pointed out in detail above.

It is obvious that the illustrative forms of shape and arrangement are not the only ones which 30 can be employed in accordance with this invention, and within the scope of the appended 35 claims.

Having thus described the invention, what we claim as new and desire to secure by Letters Patent, is:

1. A device for substantially eliminating noise incident to the discharge of liquid under pressure into a receptacle, comprising a conduit having an outlet end discharging into said receptacle 40 and a cylindrical inlet portion adapted to be connected with the pressure line, said cylindrical portion merging by gradual change of shape into a flattened outlet end portion having closely spaced walls, for retarding the flow of the liquid 45 into the receptacle with consequent substantial elimination of the noise.

2. A device for substantially eliminating noise incident to the discharge of liquid under pressure into a receptacle, comprising a conduit having 50 an outlet end discharging into said receptacle, and a cylindrical inlet end portion adapted to be connected with the pressure line, said cylindrical portion merging by gradual change of shape into a flattened outlet end portion having the walls 55 thereof spaced apart a distance less than 0.125 inch, for retarding the flow of liquid into the receptacle with consequent substantial elimination of the noise.

3. A device for substantially eliminating noise 60 incident to the discharge of liquid under pres-

sure into a receptacle, comprising a tube having an outlet end extending into and discharging into said receptacle, and a cylindrical inlet end portion adapted to be connected with the pressure line, said cylindrical portion merging by 5 gradual change of shape into a flattened outlet end portion, said flattened outlet end portion being of uniform dimensions for a distance of not less than one-quarter of an inch from the discharge end and having the opposed walls thereof 10 spaced apart a distance less than 0.125 inch for retarding the flow of the liquid into the receptacle with consequent substantial elimination of the noise.

4. A device for substantially eliminating noise 15 incident to the discharge of liquid under pressure into a receptacle comprising a tube extending into and discharging into said receptacle, said tube having a straight axis with a cylindrical inlet end portion adapted to be connected with 20 the pressure line, said cylindrical portion merging by gradual change of shape into a flattened outlet end portion, which flattened end portion is of substantially uniform cross-sectional dimensions for a distance in the direction of flow 25 in excess of one-quarter of an inch, the distance between opposed walls of said tube being between 0.010 and 0.060 inch for retarding the flow of liquid into the receptacle with consequent substantial elimination of the noise. 30

5. A device for substantially eliminating noise incident to the discharge of liquid under pressure into a receptacle comprising a conduit having an outlet end extending into and discharging into said receptacle, and an inlet portion adapted 35 to be connected with the pressure line, said outlet end portion being shaped so as to provide closely spaced opposed walls which are substantially the same distance apart at all points and from which the liquid is delivered in a sheet-like 40 form, for retarding the flow of the liquid into the receptacle with the consequent substantial elimination of the noise.

6. A device for substantially eliminating noise 45 incident to the discharge of liquid under pressure into a receptacle comprising a conduit having an outlet end extending into and discharging into said receptacle, and an inlet portion adapted to be connected with the pressure line, 50 said outlet end portion being shaped so that one of the dimensions of its cross-section is at least three times the opposite dimension and so that all filaments of the liquid are less than 0.0625 inch from the nearest wall of the conduit, for 55 retarding the flow of the liquid into the receptacle with consequent substantial elimination of the noise.
